SAFETY GOGGLES

Charles L. Wagner, Pittsburgh, Pa.

Application March 28, 1941, Serial No. 385,753

2 Claims. (Cl. 2—14)

This invention relates to improvements in safety goggles, and more particularly to safety goggles adapted for use under conditions of high temperature and the hazards of flying sparks, particles, etc.

For example, men working around melting furnaces and the like are subjected to dangerous heat and to flashes from the furnaces, necessitating a high degree of protection for the eyes. The heat is frequently so intense as to excessively heat the metal parts of the goggles worn by the workers and cause burning of the face thereby. Also, unprotected goggles are ineffective to prevent the entrance of sparks or flying particles around and behind the goggles, thereby endangering the eyes. Further, such goggles are ineffective to properly shield the eyes of the wearer from perspiration caused by the excessive heat to which the worker is subjected.

Among the objects of my invention are:

To provide safety goggles completely heat insulated against contact of the metal parts thereof with the face of the wearer; to provide such insulation of a form and character so as to readily conform the same to the face contours of the wearer and to adequately absorb perspiration; and to render such a construction completely flash-proof and entirely safe against sparks, flying particles, and the like.

Additional objects and advantages will become apparent from the following description taken in connection with the accompanying drawing wherein:

Fig. 1 is a front elevational view of a pair of safety goggles embodying my invention;

Fig. 2 is a rear elevational view thereof;

Fig. 3 is a side elevation of the goggles;

Fig. 4 is a top plan view thereof; and

Fig. 5 is an enlarged cross sectional view taken on the line V—V of Fig. 1.

Referring to the drawing, A designates a pair of safety goggles constructed in accordance with my invention, including lenses 2 of shatter-proof glass mounted in lens frames 3 having bows or earpieces 4, said lens frames 3 being connected by a central nosepiece or bridge 5 between the lenses. The goggles also have ventilated rearwardly extending side guards 6 hinged at 7 to the outer portion of each frame 3 to rearwardly extending metal flanges 8 thereof, said flanges preferably extending substantially around each of the said frames.

For the purpose of protecting the face of the wearer against contact with the metal frame of the goggles, I provide insulating pads 9 of leather

secured to the inner portions of the lens frames 3 adjacent the nose, said pads being fastened as by riveting to the flanges 8 of the frames. The pads are secured to and extend substantially around the adjacent inner one-half portions of the lens frames and have free terminal portions or flaps 10 overlying the hinges 7 of the side guards 6, said flaps being of sufficient length to substantially overlie the upper and lower contours of the said side guards 6, as particularly shown in Figs. 2 and 3.

The insulating pads 9 have their free longitudinal edges extending rearwardly a sufficient distance to provide flexibility and thereby enable the same to readily engage and conform to the contours of the face of the wearer in the regions between the eyes and nose at the center portion of the goggles, the flaps 10 of the pads increasing in dimension rearwardly and outwardly of the goggless for positive self-aligning conformity with the face portions above and below the eyes of the wearer. Similarly, those portions of the pads 9 at the top and bottom of the frames adjacent their terminal flaps 10 are tapered to merge with the said flaps in proper conformity with the face contours above and below the eyes.

The curved outer terminal edges of the side guards 6 are covered with a protective insulating pliant binding 11 to engage and form a protective closure around the face portions outwardly beyond the eyes of the wearer, said bindings 11, the pads 9 and flaps 10 providing a completely encircling, self-aligning closure between the goggles proper and the face of the wearer.

My invention also includes a nose shield 12 consisting of a nose pad 13 of leather extending from the nose piece or bridge 5 downwardly between the lens frames 3 and the inner portions of the pads 9, and following the inner contours of the lens frames to points on the lower edges thereof adjacent the junctures of the lower flaps 10 with their respective pads 9, said nose pad terminating in a downwardly and outwardly flared skirt 14 extending below the frames a sufficient distance to adequately overlie and cover the nose of the wearer. The nose pad 13 is also made full or pouch-like so that the same will readily and comfortably conform to the nose contour.

In addition, the nose shield 12 includes a reinforcing and stiffening band 15 of fine wire mesh gauze or screen secured to the upper portion of the shield and on the outer surface thereof between the lens frames, said band extending downwardly at least to the point of substantial divergence of the lens frames away from the

nose. In addition to its stiffening and reenforcing properties, the wire mesh of the band 15 functions to intercept and dissipate radiated heat, thereby protecting the leather nose shield as well as the nose.

The shield 12 is formed by stitching the wire gauze or screen 15 to the pad 13, and then stitching the latter to the inner adjacent portions of the insulating pads 9, thus forming a complete over-all insulating and protecting covering for the metal portions of the goggles and for the nose to shield against burning the face of the wearer.

I have found that excellent results are obtained from the use of Carpincho leather or tanned wild pigs' hide for the pads 9, flaps 10, 15 bindings 11, and nose pad 13. This type of leather remains soft and pliant over long periods of time under extreme heat and will adequately absorb perspiration. Also, this leather will resist and deflect hot sparks or foreign particles encountered in the field of use for which the present goggles are intended.

Various changes and modifications are contemplated within the scope of the following claims.

I claim:

5. 1. Safety goggles including a pair of lens frames, heat insulating pads of pliant material disposed about and secured to the frames, and a nose shield of heat insulating pliant material disposed between said frames, said nose shield including a band of fine wire gauze disposed 10 thereover on the outer surface of the shield between the frames.

15. 2. Safety goggles including a pair of lens frames, heat insulating pads of pliant material disposed about and secured to the frames, and a nose shield of heat insulating pliant material disposed between said frames, said nose shield including a band of fine wire gauze disposed 20 thereover on the outer surface of the shield between the frames, and extending downwardly at least to the point of substantial divergence of the lens frames from the nose of the wearer.

CHARLES L. WAGNER.
